UNITED STATES PATENT OFFICE.

WILLIAM WESTLAKE, OF BROOKLYN, NEW YORK.

DESIGN FOR A VASE CUSPIDOR.

SPECIFICATION forming part of Design No. 25,547, dated May 26, 1896.

Application filed February 6, 1896. Serial No. 578,283. Term of patent 14 years.

To all whom it may concern:

Be it known that I, WILLIAM WESTLAKE, a citizen of the United States, residing at Brooklyn, in the county of Kings and State of New York, have invented and produced a new and original Design for Vase Cuspidors, of which the following is a specification, reference being had to the accompanying drawings, forming a part thereof.

10 In the accompanying drawings, Figure 1 is a perspective view of a cuspidor embodying my design, and Fig. 2 is a plan of the same.

The leading feature of my design consists in a cuspidor with a vase-like body, bulbous 15 below, contracted near its upper part, and outwardly flared above said contracted portion, loop-like handles which contact with the

bulbous portion of the body at their lower ends and with the said flared portion of the body at their upper ends, and a funnel the 20 rim of which rests on the top of said body.

A is the body, provided with handles B B. C is the funnel, and D is the base having feet d.

What I claim is—

25 The design for a vase cuspidor, as herein shown and described.

In witness whereof I have hereunto signed my name in the presence of two subscribing witnesses.

WILLIAM WESTLAKE.
